UNITED STATES PATENT OFFICE

EDWARD H. FRENCH, OF COLUMBUS, OHIO

PROCESS OF RECOVERING RESINOUS BY-PRODUCTS IN THE MANUFACTURE OF
WOOD PULP

Original application filed August 15, 1925, Serial No. 50,526. Divided and this application filed October 29, 1928. Serial No. 315,784.

In the manufacture of paper pulp produced from resinous woods by the so-called "sulphate" process the wood is cleaned and chipped, placed in a digester where it is treated with a solution containing sodium sulphid (Na_2S) and caustic soda, the wood being cooked with steam under pressure in this liquor for a period of several hours. The turpentine of the mass is recovered by distillation and the digester is blown, the pulp separated from the pulping liquor (sometimes called "black liquor"), and the latter is evaporated to a thin paste, and burned in a furnace for the purpose of consuming the organic matter and converting the sulphates in the mass to sulphids and carbonates.

During the cooking of the wood, the pulping liquor ("black liquor") acquires a large quantity of resinous substances such as rosin and rosin oils in the form principally of sodium resinate as the result of the combination of the caustic soda with the abietic acid of the rosin of the wood. Many attempts have been made to recover the sodium resinate but, as far as I am aware, without commercially satisfactory results. Among such attempts may be mentioned (1) the separation of a portion of the resin from the black liquor by cooling the latter, and (2) the precipitating or "salting out" of some of the resins from the "black liquor" by the use of an excess of alkali or of salt,—but such methods invariably give small yields of resins such as rosin, and the material thus obtained cannot be satisfactorily refined by any of the known methods.

In the plants operating on resinous woods for the manufacture of wood pulp prior to my invention, resin-containing black liquor has had value only as fuel for firing the black ash furnace used to decompose the sodium sulphate into sodium carbonate and sodium sulphid.

The object of this invention therefore is to provide an improved and economic method of recovering the resinous content of alkaline liquors containing resinate, such as pulping liquor, especially that resulting from the sulphate or soda process of paper pulp manufacture, in a form and quality equaling,

if not superior to that obtained directly from the crude resin gum.

My invention is particularly effective in treating the liquor obtained from the stumps of the long-leaf pine which contains 400 to 700 pounds of rosin to the cord, but its employment is profitable in the treatment of liquors obtained from the pulping of woods having a smaller content of rosin.

The chemical formula of the abietic acid is given by some authorities as $C_{20}H_{30}O_2$ and by others as $C_{19}H_{28}O_2$ thus signifying a molecular weight of approximately 302 and 288 respectively.

In the "sulphate" process of manufacturing pulp the alkali employed is usually derived from "salt cake" (impure sodium sulphate) which after passing through the black ash furnace is changed, in the presence of organic matter therein, to sodium carbonate and sodium sulphid as already indicated. Therefore assuming, as an example, that the rosin content of a cord of wood is 500 pounds, there will be required about 100 to 125 pounds of "salt cake" to produce the amount of sodium hydroxide or sulphid necessary to neutralize the abietic acid content of the resinous matter of the wood. The sodium resinate contained in the spent pulping liquor is soluble in the latter.

In carrying out my process I add sufficient nitre cake (impure sodium acid sulphate) to the black liquor above referred to so as to precipitate all of the sodium resinate in the form of rosin, this reaction being accompanied by released and precipitated ligneous acids. Nitre cake is considered herein on account of its pronounced acid properties as constituting for present purposes an acid. Simultaneously with the precipitation of the rosin the combined sodium of the resinate and of the organic acids present which have been derived from the wood pulp,—such as formic and acetic acids, unite with the sulphate ions of the nitre cake to form sulphates which in passing through the standard black ash furnace are again converted into sodium sulphid and sodium carbonate, both of which may be used in the pulping process. There thus results an additional quantity of sodium

sulphate due to the use of the nitre cake, such additional quantity amounting to about 50% of the nitre cake employed. By my process, therefore, I simultaneously secure 5 two valuable results, namely, the recovery of rosin from the spent pulping liquor, and the recovery of the sodium sulphate at a very low cost. The amount of nitre cake needed for complete precipitation of the resins 10 should be determined in each batch of spent liquor by analyzing it for alkalinity and sodium resinate content by the standard methods of analysis, because the resinous content of wood varies according to the variety of wood used as well as according to the 15 part of the tree from which it comes.

In the black ash furnace above mentioned, which is used for the purpose of converting the impure sodium sulphate into sodium sulphid and sodium carbonate, the reactions taking place form gases containing sulphur dioxide which go into the atmosphere as objectionable fumes. Should nitre cake be unavailable for economic reasons, I pass the 20 gases formed in the black ash furnace through the black liquor which serve all of the functions of the more expensive sulphuric acid, the sulphur dioxide formed when the sodium sulphate is heated sufficiently in the 25 presence of organic matter uniting with the water present to form sulphurous acid which precipitates the rosin from the sodium resinate in the same manner as when nitre cake or sulphuric acid is used. This procedure 30 not only effects the precipitation of the rosin and any accompanying water-insoluble organic acids and ligneous impurities, but it eliminates at the same time the objectionable fumes mentioned above.

40 In the accompanying drawings:

Figure 1 is a plan view of the apparatus employed in carrying out the present invention;

Figure 2 is a side elevation thereof; and 45 Figure 3 is a vertical sectional view of the tank employed in the separation of the rosin from the black liquor.

One convenient method for carrying out the first step of my process, that is the conversion of the soluble sodium resinate in the black liquor into rosin, is shown in the accompanying drawings, in Figure 1 of which A, A', and A'' are tanks in which black liquor is treated for the purpose of liberating rosin from the sodium resinate. Figure 3 shows a cross-section of one of the above-mentioned tanks. At the upper part of each of the tanks is a circular trough or colander having the upper part perforated, 50 and within these colanders are the steam coils 5. Each colander is provided with a rosin outlet trough 6. Suspended in the center of the top of the respective tanks A, A' and A'' are the conical deflectors 7. Immediately below the colander is the black liquor

outlet 8, having the regulating valve 9 therein. Near the bottom of each of these tanks is a perforated coil 10.

To carry out the first step of the operation, the black liquor is fed into the tank A' through the feed-line 1, the flow being regulated by the valve 2. After the tank has been filled to a point above the outlet 8, the valve 9 is regulated so that the height of the liquor is below the opening in the side of the colander. Acid preferably in gaseous form such as the acid gas from the black ash furnace described above and which contains sulphur dioxide, or as obtained from any other suitable source, is pumped through the perforated coil 10 into the tank where it reacts with the sodium resinate to liberate rosin, the latter of which is carried to the surface of the liquor with the excess of the gases introduced into the tank, substantially as fast as the former is formed.

The next step in my process is to separate the precipitate from the liquor. This is done by decantation or by filtering the mixture. The decantation is aided by the conical deflector 7 shown in Figure 3, the impure rosin being carried into the trough 6 by means of the colander heated by the steam coils 5, and from there into the solvent tanks B and B'. The precipitate, which contains many impurities such as various organic acids and other ligneous matter, is then digested at atmospheric pressure with an organic solvent such as benzol, gasoline, toluol, or kerosene in quantity sufficient to dissolve the rosin and rosin oils. The dissolving of the rosin and rosin oils can be carried out at ordinary atmospheric temperatures by means of the agitator 12, (Figure 1). After the solution has been accomplished, the liquid is ready for 95 distillation.

This solution of resinous matter resulting from the above-mentioned digestion is then distilled under a reduced pressure, and when this distillation is carried out in a glass apparatus with about 4 cm. of mercury pressure it can be distilled over with the rosin practically undecomposed,—but in iron stills it is difficult to prevent some decomposition of the rosin into a hydrocarbon variously known as colophene or abietene which is produced upon the elimination of the carboxyl group from the rosin acid.

Because of the decomposition which takes place when the pressure is increased or in the presence of metals, it is advisable in the distillation in a metallic still to further reduce the boiling point of the rosin by first preheating the solution of rosin and atomizing the mixture by means of pressure on the liquid, forcing it through a spray or atomizing nozzle into a vacuumized chamber, and condensing fractionally both the organic solvent and the rosin contained therein, the vapor from the organic solvent thus serving sufficiently 120 125 130

to reduce the boiling point of the rosin itself and therefore prevent its decomposition. The resultant crystallizable rosin distillate is then filter-pressed to separate it from any 5 oils condensed therewith, and it is then melted, thus forming a very pure rosin substantially free from objectionable impurities.

By referring to Figures 1 and 2 of the drawings the manner of carrying out the above step 10 will be understood. The solution of rosin in gasoline in the solvent tanks B and B' is forced by the pump 13 through the line 15 to the preheater 29 where it is heated to the proper temperature, and from thence is forced to the pressure tank 16. Here a pressure sufficiently high to atomize the rosin as 15 it flows into the stills D, D' and D'', is maintained. The respective stills D, D', and D'' have connected therewith the condensers E, 20 E', and E'', and the latter have liquid drain connections leading to the respective distillate receiving tanks F' to F''. A high vacuum is maintained upon the various stills and condensers by the vacuum pump 17 which is connected to the line through condenser G.

Where the final product desired is rosin, the condensers E, E', and E'' are maintained sufficiently hot by the control of the cooling water thereto to maintain the solvent in the 30 gaseous form but sufficiently cool to condense the rosin. The steam coil 18 is provided for the purpose of maintaining the receiving tanks F' to F'' at a temperature to prevent the condensation of the solvent, which therefore passes to the condenser G and is there 35 condensed and tapped off for reuse in the process. The rosin is drawn off through the valve 26.

For atomizing the rosin-solvent solution 40 into the stills, atomizing pressures will vary, depending upon such factors as the type of nozzle used, the volume of solution to be sprayed in a given time, and the like. The said pressures usually range from ten pounds 45 per sq. in. upward. The temperature of distillation is dependent upon such factors as the kind of solvent used and the degree of vacuum obtainable. Where a good grade of kerosene is used, and an absolute pressure 50 of about 4 cm. of mercury is obtainable on the still, the temperature of the liquid in the still will range around 240° C., providing two parts of the solvent are used to one part of the rosin.

55 It is well known that from 35% to 40% of the rosin produced in this country enters into the manufacture of rosin soap, and for this purpose the rosin acids are neutralized or saponified with soda ash or caustic soda. I 60 have discovered that the rosin in the organic solution aforementioned either before or after distillation may be recovered from the solution by adding an aqueous solution of an alkali to the rosin solution and agitating 65 the mixture thereby neutralizing the

abietic acid which will separate out first as an emulsion but later on standing it will break down so that it will be in solution in the water, thus being separated from the organic solvent which will form a distinct layer on 70 the top that can be decanted to be again used to dissolve succeeding batches. The solution of sodium resinate in water is then evaporated, leaving the granular sodium resinate as a residue useful in manufacturing soap or 75 paper size.

When sodium resinate is to be manufactured, the entire distillate is condensed in the condensers E, E', and E'', and collected in the receiving tanks F' to F''. The resultant 80 condensate is forced by means of pump 23 to the tank H in which the rosin is converted to sodium resinate by means of caustic soda or the like. The tank H is equipped with means for agitating the liquid during the 85 neutralization step, and it also has connected thereto the condenser I and the pump 25, the procedure involved in the resinate production being disclosed and claimed in my co-pending application No. 172,821, filed March 90 4, 1927.

This application is a division of my co-pending application No. 50,526, filed August 15, 1925, now matured into Patent #1,693,586 95 issued Nov. 27, 1928.

My invention is susceptible of modification within the scope of the appended claims.

I claim:

1. The process of recovering rosin from alkaline liquors containing resinates which comprises the step of passing an acid gas through the said liquors to liberate at least part of the rosin content thereof. 100

2. The process of recovering rosin from alkaline liquors containing resinates which comprises adding an acid material to the liquor in an amount sufficient to decompose at least a part of the resinates into rosin, and passing a gas through the liquor thereby to float the rosin to the surface of the liquor. 105

3. The process as defined in claim 2 in which an acid gas is used both to decompose the resinates and to float the thus-formed rosin to the surface of the liquor. 110

4. The process as defined in claim 2 in which the decomposition of the resinates and the floating of the thus-formed rosin to the surface of the liquor is effected substantially simultaneously. 115

5. The process as defined in claim 2 in which sulphur dioxide gas is used both to decompose the resinates and to float the rosin to the surface of the liquor. 120

6. The process as defined in claim 2 in which the resinates are decomposed and the precipitated rosin floated to the surface of the liquor by means of waste gases obtained from the combustion of black ash. 125

7. The process of recovering rosin from alkaline liquors containing resinates which 130

comprises the step of passing sulphur dioxide-containing gases through the said liquors to liberate at least part of the rosin content therein.

5 8. In the process of recovering rosin from alkaline pulping liquors containing resinates, the step of passing therethrough the combustion gases from the calcination of black ash.

9. In the process of recovering rosin from 10 alkaline liquors containing resinates, the steps of passing an acid gas through an alkaline solution of the resinates in amount sufficient to liberate at least part of the rosin contained therein, floating the liberated rosin 15 to the surface of the liquor; and decanting the rosin from the liquor.

10. The process of recovering rosin from alkaline resinate solutions which comprises the step of passing an acid gas through the 20 said solution in amount sufficient to neutralize at least a part of the resinates contained therein to form rosin, and floating the rosin to the surface of the solution.

In witness whereof I have hereunto set my
25 hand this 27th day of October, 1928.

EDWARD H. FRENCH.
